(57) **CLAIM**

The ornamental design for a diving apparatus as shown and described.

DESCRIPTION

1. Diving apparatus

1.1: Front

1.2: Top front perspective

1.3: Back perspective

1.4: Left

1.5: Right

1.6: Top back perspective

1.7: Front left perspective

1.8: Back left perspective

1.9: Top perspective

1.10: Top perspective

1.11 : Back perspective

The broken lines depict portions of the diving apparatus that form no part of the claimed design. The decal feature on the front of the cylinder, the rectangular feature with the text

(Continued)

inside "NDEEN" on the strap, and the text inscription on the valve feature are not part of the claim.

1 Claim, 11 Drawing Sheets
